UNITED STATES PATENT OFFICE.

WALTER P. ALBERT, OF EAST ORANGE, NEW JERSEY, ASSIGNOR TO WESTERN ELECTRIC COMPANY, INCORPORATED, OF NEW YORK, N. Y., A CORPORATION OF NEW YORK.

TELEPHONE SYSTEM.

Application filed October 26, 1923. Serial No. 670,820.

To all whom it may concern:

Be it known that I, WALTER P. ALBERT, a citizen of the United States, residing at East Orange, in the county of Essex and State of New Jersey, have invented certain new and useful Improvements in Telephone Systems, of which the following is a full, clear, concise, and exact description.

This invention relates to telephone systems, and more particularly to private branch exchange systems of the machine switching type.

With the general trend of telephony toward mechanical operation, it is necessary that private branch exchanges be equipped with apparatus necessary in completing connections between machine switching subscribers, and in extending calls to other machine switching exchanges.

It is an object of this invention to furnish a private branch exchange attendant with the minimum amount of equipment necessary in completing the various types of connections common to a private branch exchange.

This object is attained in accordance with a feature of the invention by the provision of a cord circuit and an associated attendant's dial and telephone circuit, wherein a plurality of keys are provided, which may be operated singly or collectively, to connect the dialing equipment with either the front or rear end of the cord circuit, as the connection to be established may require.

Another feature of the invention resides in a circuit arrangement wherein the operation of a listening key in a cord circuit to connect the attendant's telephone set thereto, renders the operation of a second listening key ineffective to connect the telephone set to a second cord circuit until the first key is restored. By this arrangement, an attendant is unable to listen in on more than one connection at a time.

A further feature of the invention resides in a trunk circuit wherein means are provided for preventing the false operation of the trunk signal when the private branch exchange attendant disconnects her cord circuit from the trunk.

A still further feature of the invention resides in an arrangement for preventing the false operation of a tie line pulsing relay when a call, incoming from a central office exchange, is extended over the tie line by way of the attendant's cord circuit. In effecting this feature, a relay in the tie line circuit is provided which controls the connection of the pulsing relay to the jack of the tie line. When the front end of the cord, employed in completing a connection, is connected to a central office trunk and the rear end to a tie line and the talking and dialing key actuated, the central office battery will be connected straight through the cord circuit to the jack of the tie line. When the through dialing key is actuated, a pair of relays in the operator's dial and telephone circuit operate to disconnect the central office battery from the tie line, connect a holding bridge across the central office trunk and then cause the operation of the above mentioned tie line relay which connects the tie line pulsing relay to the jack of the tie line.

The above and other objects of this invention will be readily understood from the following detailed description made with reference to the accompanying drawings, in which Fig. 1 shows a local P. B. X. machine switching subscriber's line and the automatic equipment necessary for signaling an attendant at the private branch exchange; Fig. 2 shows a P. B. X. attendant's cord circuit involving features of this invention; Fig. 3 shows the attendant's dial and talking equipment which functions with the cord circuit shown in Fig. 2; Fig. 4 shows a central office trunk outgoing from the private branch exchange, and the automatic equipment necessary in establishing a call therefrom to a machine switching subscriber's line; and Fig. 5 shows a portion of a tie line, by means of which a connection may be established from one private branch exchange to another private branch exchange.

Connection from P. B. X. to C. O. (attendant dialing over front end).

Assuming that a machine switching subscriber at station A desires to converse with

a subscriber at station B, whose line terminates in a distant machine switching exchange, the operation is as follows:

- Upon removal of the receiver at station 5 A, an operating circuit for slow release relay, 100 is established, which may be traced from battery, winding of relay 100, back contact and inner left-hand armature of relay 101, the subscriber's line loop to ground, over the 10 outer left-hand armature and back contact of relay 101. Relay 100 establishes an obvious circuit for the low resistance right-hand winding of relay 101, which in operating, actuates the line switch plunger 102. 15 The plunger 102 causes the tip, ring and sleeve conductors of the line A to be connected to corresponding brushes of a selector switch S of the step by step type well known in the art. 20 The subscriber then actuates the dial associated with the line A, in order to send out a code of impulses, such as 9, which digit, when dialed, causes the selector S to be operated to select a group of trunks and 25 automatically hunt for and connect the brushes to an idle trunk leading to the private branch exchange attendant's position.

When an idle trunk is reached a ground, associated with the terminal 103, causes the 30 left-hand high resistance winding of relay 101 to become energized in an obvious circuit. Relay 101 by pulling up its outer and left hand armature, and plunger 102, and by causing the connection of ground 103 to the line, as just explained, serves to connect ground to the respective sleeve terminals of jack J and connector C which are multiple terminals of the calling line. This ground causes the line A to test "busy" 35 on all incoming calls.

Relay 101 also opens the operating circuit for slow release relay 100, which, after an interval, releases its armature, thereby opening the circuit for the right-hand winding of relay 101. The slow release characteristic of relay 100 enables relay 101 to remain operated over its right-hand winding until the ground from the selector circuit completes the energizing circuit for the left-hand winding. The line switch plunger 102 is accordingly held actuated as long as the connection is maintained.

When the tip and ring terminals, 104 and 55 105, of the idle trunk L are connected to corresponding wipers of the selector switch S, relay 106 operates over the subscriber's line loop, causing the lamp 107 to be illuminated as an indication to the private branch exchange attendant that there is a 60 call awaiting her attention. The attendant then inserts the rear end plug 200 of the cord circuit K into the trunk jack J' corresponding to the illuminated lamp 107. This operation closes the local jack contacts 109, causing cut-off relay 108 to op-

erate in an obvious circuit, whereupon relay 106 releases and lamp 107 is extinguished.

Answering supervisory relay 201 in the attendant's cord circuit, now operates in a 70 circuit extending from battery, armature 223 and back contact of relay 202, lower winding of retardation coil 203, contact 250 of key 210, winding of relay 201, lower normal contacts of ringing key 205, ring contacts of plug 200 and jack J', terminal 105 and the corresponding brush contacts 110 of the line switch, over the subscriber's line loop, contacts 111 of the line switch, brush and terminal 104, tip contacts of jack J' 80 and plug 200, upper normal contacts of ringing key 205, contacts 228 of key 210, upper winding of retardation coil 203 to ground over the inner left-hand armature and back contact of relay 202. Relay 201 85 in operating, prevents lamp 206 from illuminating at this time and prepares a circuit for relay 207. The calling supervisory lamp 208, however, illuminates in a circuit 90 extending from grounded battery, lamp 208, back contact and armature 221 of relay 202, back contact and armature of calling supervisory relay 209, sleeve contacts of plug 200 and jack J', to ground over the right-hand armature and front contact of relay 108.

The attendant now actuates the talk and dial key 204, to connect her headset with the calling line. At the contacts 211 of key 204, a circuit for relay 212 is established, which may be traced from grounded battery, lower winding of relay 212, key contacts 211, conductor 224 to ground over the back contact and upper armature of relay 325. Relay 212, at its inner upper armature, establishes an energizing circuit for relay 213 by way of the contacts 214 of key 204. Relay 213, at its inner upper armature, causes relay 325 to operate in a circuit extending from grounded battery 100 through the winding of relay 325, conductor 230, winding of relay 212, to ground over the front contact and inner upper armature of relay 213. This circuit acts as a holding circuit for relay 212 after the circuit through its energizing winding is opened by the operation of common relay 325, so that it is now impossible to energize another relay, similar to relay 212, associated with another cord circuit, should its 110 associated talk and dial key 204 be operated. It is, therefore, apparent that the attendant cannot listen-in on more than one connection at a time.

Relay 325 at its lower armature and front contact, connects the left-hand windings of repeating coil 341 across the right-hand windings of repeating coil 365 by way of the outer right-hand armature and back contact of relay 339 and condenser 360. The 125 130

operator's headset 332 is now bridged across the rear end of the cord circuit since relay 212, in attracting its armatures 215 and 216, connects the tip and ring conductors of the rear end of the cord circuit to conductors 234 and 233, respectively, which in turn are connected to the right-hand windings of repeating coil 365 by way of the normal contacts of relay 335, conductors 342 and 337, conductor 338 and the two right-hand armatures and back contacts of relay 339. The private branch exchange attendant is, therefore, in a position to converse with the calling subscriber. At its alternate make-before-break contacts, 217 and 218, relay 212 connects the retardation coil 351 across the front end of the cord by way of conductors 253 and 254 and the outer armatures and back contacts of relay 352 and the normal make-before-break contacts of relay 350.

The attendant now requests the nature of the call from the calling subscriber, and is informed that a subscriber's line B, which terminates at a distant machine switching exchange, is desired, whereupon she tests for an idle trunk leading to the machine switching exchange in the well known manner. Assuming the central office trunk M to be the first idle trunk encountered, the attendant inserts plug 220 into jack 400 and actuates the dial 348 in accordance with the number of the desired line.

When plug 220 is inserted in jack 400 of the central office trunk M, relays 202 and 402 operate in a circuit extending from battery, winding of relay 402, contacts 401 of jack 400, sleeve contacts of jack 400 and plug 220, winding of relay 202 to ground. Relay 402 locks to the sleeve of jack 400, and at its two right-hand armatures, connects ground and battery, respectively, to the two plates of condenser 405 by way of the right-hand winding of relay 403. Battery is connected to the condenser 405 by way of both the left-hand winding of relay 403 and lamp 404, neither of which, however, are energized since there is no complete direct current path established. The charge on the condenser at this time is for a purpose hereinafter to be set forth.

Relay 202, at its armature 221, removes the control of lamp 208 from the calling supervisory relay 209 and causes it to be extinguished. At its armatures 223 and 222, it disconnects the battery and ground, through the winding of retardation coil 203, which, originally supplied the calling party with talking battery. The operation of relay 202 does, however, not cause the release of answering supervisory relay 201 which is now held operated in a circuit extending from grounded battery 415, winding of relay 406, back contact and inner armature of relay 407, contact 409 of jack 400, ring

contacts of jack 400 and plug 220, lower normal contacts of key 229, contacts 218 of relay 212, conductor 254, upper outer armature and back contact of relay 352, conductor 342, upper normal contacts of relay 335, conductor 234, front contact and armature 216 of relay 212, contacts 227 of key 210, winding of calling supervisory relay 209, contacts 250 of key 210, winding of answering supervisory relay 201, lower normal contacts of key 205, ring contacts of plug 200 and jack J' and thence over the established connection including line A, back to the tip contacts of jack J' and plug 200, upper normal contacts of key 205, armature 215 and front contact of relay 212, conductor 233, lower normal contacts of relay 335, conductor 337, back contact and outer lower armature of relay 352, conductor 253, contacts 217 of relay 212, upper normal contacts of key 229, tip contacts of plug 220 and jack 400, to ground over the back contact and outer armature of relay 407. Relays 209 and 406 also operate in this circuit. Relay 209 performs no function since lamp 208 has already been extinguished by the operation of relay 202. At its armature 225, relay 202 connects the ring conductor of the rear end of the cord K to the contacts 227 of key 210. In attracting its armature 226, relay 202 causes relay 207 to operate in a circuit extending from grounded battery, over the armature 226 and front contact of relay 202, winding of relay 207, front contact and armature of relay 201, and thence to ground on the sleeve circuit.

Relay 207, in attracting its armature 260, connects the two upper windings of retardation coil 203 to the normal contacts 227 and 228 of key 210, and at its armature 261 short circuits relay 209, causing it to release. As hereinbefore described, the retardation coil 351 is connected across the front end of the cord circuit and it will also be noted that at this time the two upper windings of retard coil 203 and the subscriber's substation set are connected in parallel with retard coil 351. Relay 406, operating in the circuit hereinbefore traced, causes the low resistance winding of relay 407 to be energized, whereupon the line switch plunger 450 is actuated to connect the trunk conductors to the terminals of the selector switch S'.

Dialing.

The attendant now operates the dial 348 to select the number wanted by the calling subscriber at A and when the dial 348 leaves normal position the slow releasing relay 339 operates in an obvious circuit. In attracting its two right-hand armatures, relay 339 disconnects the operator's telephone set from the rear end of cord circuit, and, at its left-hand armature, causes relay 350 to operate

in an obvious circuit. Relay 350, at its lower armature, disconnects the retardation coil 351 from the front end of the cord circuit, and substitutes the dial contacts of dial 348 therefor. At its upper armature, it causes relay 335 to operate in a circuit which may be traced from grounded battery, through the winding of relay 335, over the front contact and upper armature of relay 350, contacts 391 of relay 352 to ground over the front contact and upper armature of relay 325.

Relay 335, in operating, locks itself in the circuit just traced, independent of relay 350. At its two outer armatures, relay 335 supplies the calling subscriber with talking battery over a path extending from battery, contacts 392 of relay 363, resistance element 364, lower left-hand winding of repeating coil 365, lower armature and front contact of relay 335, conductor 233, front contact and armature 215 of relay 212, upper normal contacts of key 205, tip of plug 200, thence out over the established connection and back to the ring contact of plug 200, lower normal contact of key 205, winding of supervisory relay 201, contacts 250 of key 210, outer left hand armature 261 and contacts of relay 207, contact 227 of key 210, armature 216 and front contact of relay 212, conductor 234, upper armature and front contact of relay 335, upper left-hand winding of repeating coil 365, resistance element 368, to ground over the contacts 398 of relay 363. It is now apparent that relay 201 remains energized at all times, being supplied with battery, first from the cord circuit K, then from the line switch connected to trunk M, and finally from repeating coil 365 in the attendant's dialing circuit. By this arrangement the subscriber may flash the attendant at any time during the connection.

The attendant in operating the dial in accordance with the desired number actuates the selector S' and connector C' in the well known manner to connect the conductors of trunk M to the terminals of the desired line B and need not be described in detail. It will be understood as was stated in connection with relay 100 that relay 406 maintains the line switch plunger 450 operated during the interval between the energization of the right-hand winding of relay 407 and the seizure of an idle selector switch S', and that when the connector C' is seized a ground on terminal 410 thereof holds relay 407 operated.

When the connector C' reaches the called line B, and the same is idle, ringing current will be connected to the subscriber's line in the well known manner, to signal the called subscriber. When the called subscriber responds to this signal, and removes

the receiver from the switchhook, back bridge relay 411 operates, causing the reversal of battery over the established connection in the well known manner. This reversal does not affect relay 403 at this time since its right-hand winding is disconnected from the trunk M at the back contacts of relay 402.

If, after completing the dialing operation, the attendant fails to restore the talk and dial key 204 the relay 339 will have restored when the dial returns to normal, so that the circuit for relay 350 is opened, whereupon this relay releases. Relay 335, however, is held operated over its locking circuit to ground on the front contact and upper armature of relay 325. The left-hand windings of the repeating coil 365 are then bridged across the tip and ring conductors of the rear end of the cord circuit by way of the armatures and front contacts of relay 335, conductors 233 and 234 and the front contacts and armatures 215 and 216 of relay 212. The secondary winding of repeating coil 365 is connected in parallel with coil 351 and with the two upper windings of retardation coil 203, and is connected to the front end of the cord by way of the outermost armatures and back contacts of relay 352, conductors 253 and 254, contacts 217 and 218 of relay 212, to the front end of the cord circuit K. The calling subscriber may therefore now converse with the central office subscriber at station B through the attendant's telephone and dial circuit. However, should the attendant restore key 204, relay 213 releases, removing ground from the upper winding of relay 212 in series with relay 325, whereupon these relays release, the circuit for the lower winding of relay 212 being open at the contact 211 of key 204. Relay 212, in releasing, disconnects the attendant's telephone and dial equipment from the cord circuit so that the calling and called subscribers may converse directly through the cord circuit which under this condition is bridged only by the two upper windings of retardation coil 203.

At the termination of the conversation, the calling subscriber replaces the receiver on the switchhook, thereby opening the circuit for answering supervisory relay 201 which, in releasing, causes lamp 206 to illuminate over an obvious sleeve circuit. This signal serves as a disconnect signal to the private branch exchange attendant, whereupon she proceeds to take down the connection.

Removal of plug 200 from jack J' opens the sleeve circuit, thereby causing lamp 206 to be extinguished. When relay 201 releases, the circuit for relay 207 is open, whereupon this relay restores disconnecting the middle high resistance winding of re-

stardation coil 203 from the cord circuit. Only the upper winding of coil 203 is now held in bridge of the cord circuit, this bridge extending from the point 230 on the tip conductor of the cord circuit, over the contacts 228 of key 210, upper winding of retardation coil 203, armature 222 and front contact of relay 202 (which is still operated over the front end of the connection), contacts 231 of relay 207, (which is now released owing to the release of relay 201) contacts 227 of key 210, to the point 232 on the ring conductor of the cord. This removal of the high resistance winding of retardation coil from across the cord circuit is for the purpose of holding the central office switches operated after the calling subscriber replaces his receiver and until the attendant removes the plug 220 from jack 400.

When the called subscriber at station B replaces the receiver on the switchhook, relay 411 releases, restoring the original battery and ground connections to the selector switch terminals. The withdrawal of plug 220 from jack 400 also releases relays 202 and 402. The release of relay 202 restores the cord circuit equipment to normal condition.

Relay 402, on restoring, reconnects the bridge including the condenser 405 and the right-hand winding of relay 403 to the tip and ring conductors of the central office trunk M. Just prior to the release of relay 402, the upper plate of condenser 405 was connected to the negative poles of battery 412 and 413, whereas the lower plate was connected to the positive pole or ground, so that the condenser was charged to the potential of this battery which, in systems of this type, is about 48 volts. With relay 411 released, it will be noted that the negative pole of the battery 416 associated with the winding of relay 414 is connected to the ring side of the connection and thence through the right hand winding of relay 403 to the lower plate of condenser 405, whereas the positive pole or ground is connected to the tip side of the connection and thence to the upper plate of this condenser. This condition of battery and ground is just the reverse of that existing when relay 402 was operated, so that there will be a potential of about 96 volts (assuming the central office battery and the local private branch exchange

battery to be of the same voltage as will ordinarily be the case) across the right hand winding of relay 403, which will cause a current flow through this winding in the direction indicated by the arrow. Relay 403 is poled in such a manner that, when current is flowing in the direction indicated, the flux set up in the right hand winding will oppose that set up by the left hand winding when

its circuit is closed through its own front contact, so that the following action takes place: Due to the current flow in the right hand winding of relay 403, this relay will operate and close its contacts, thereby completing the locking circuit through its left hand winding. As soon as this locking circuit is completed, the flux set up in the left hand winding will oppose that set up by the right hand winding, whereupon the relay releases. This action will repeat itself until the charge on the condenser 405 has been reversed, so that the relay 403 will cause its armature to vibrate. This differential effect of relay 403, therefore, prevents this relay from permanently closing its locking circuit and causing the illumination of lamp 404 as a false indication of an incoming call. The condenser 405 is now fully charged from the connector battery 416 and when the selector switch S releases, it causes the negative pole of the line switch battery 415 to be connected to the ring conductor of the trunk and ground to the tip. This current is therefore in the same direction as the current from the connector battery 416 so that there is no reversal of current to cause any change in the charging of the condenser 405, so that there will be no current flow through the right hand winding of relay 403. The lamp 404, therefore, will not be falsely operated. It is, therefore, apparent that the differential effect of relay 403 provides an arrangement whereby the release of the automatic switches at the central office does not cause false operation of the signaling device 404.

Should the operator remove plug 220 from jack 400 before the called subscriber at B hangs up the receiver, relay 411 will still be operated so that the negative pole of battery 416 is connected to the tip conductor of the connection instead of to the ring as in the preceding case, while ground is connected to the ring instead of the tip. This is the condition which will be met by the right hand armatures of relay 402 when they restore and since this is the same condition that existed when relay 402 was operated, there will be no current caused to flow in the right hand winding of relay 403 and consequently no false signal given. The preliminary charge on condenser 405 therefore prevents false operation of lamp 404 in this case.

The subscriber, having hung up the receiver and the selectors having been released, the negative pole of battery 415 will be connected to the ring conductor of the connection and ground to the tip. This condition is the reverse of that set up by the connector battery so that the condenser 405 will discharge as hereinbefore described through the right hand winding of relay 403. The differ-

tial effect of relay 403 then prevents the permanent closure of its locking circuit to cause the false operation of lamp 404.

5 *Connection from C. O. to P. B. X.*

The trunk M is arranged for two-way operation, its central office end having multiple connector terminals shown at D. On 10 a call incoming to the private branch exchange from a central office subscriber, the subscriber actuates the dial associated with his station in order to connect the calling line to the connector terminals D in the well 15 known manner. When the trunk M is seized ringing current will be automatically connected thereto to cause the operation of relay 403 through its right hand winding. Relay 403 in operating locks up and establishes a 20 circuit for lamp 404 by way of the contacts 417 of jack 400. The illumination of lamp 404 indicates to the private branch exchange attendant that a call is awaiting her attention. She thereupon inserts plug 220 of her 25 cord K into jack 400 of the trunk M and actuates the key 204 in order to connect her headset to the cord and proceeds to set up the desired connection. The arrangement hereinbefore described in connection with 30 the release of the automatic switches on an outgoing call functions in a similar manner on the release of the automatic switches on an incoming call and it is believed unnecessary to repeat the action of relay 403 and 35 condenser 405 under this connection.

Connection from P. B. X. to C. O. (P. B. X. subscriber dialing).

40 Should the calling party at A desire a central office connection and wish to dial the called subscriber himself, he proceeds in the same manner as hereinbefore described in 45 signaling the P. B. X. attendant, who then actuates her listening key 204 to place her headset across the tip and ring conductors of the calling line. The calling party then 50 requests a "through dialing" connection. Upon receipt of such a request, the P. B. X. attendant extends the call to an idle central office trunk by way of plug 220 as in the 55 preceding description, operates the through dialing key 210 and restores the listening key 204. The insertion of plug 220 into the jack 400 of the central office trunk causes 60 relays 202 and 207 to operate as hereinbefore described so that when the through dialing key 210 is operated, contacts 250 and 228 are opened to cut off the retardation coil 65 203 from across the tip and ring of the cord. Contacts 219 of key 210 are closed, thereby cutting through the ring conductor of the cord. The function of key 210 is, 70 therefore, to place the calling subscriber's line directly across the central office trunk

so that the subscriber is in a position to dial the central office direct. On such a connection, when the calling and called subscribers hang up the receivers, the central office automatic switches are automatically released, 75 and as described in the previous connection, relay 201 is released to bring in the supervisory lamp 206 to notify the P. B. X. operator that the call has terminated and she may proceed to take down the cord. 75

Connection from one P. B. X. to another over a tie line.

In many instances a local P. B. X. subscriber desires to communicate with another subscriber whose line terminates in another P. B. X. In order to set up such a connection it is necessary for the P. B. X. attendant to employ what is known as a tie line 85 which interconnects the two P. B. X.'s.

When such a call originates at a local subscriber's station, the attendant answers in the usual manner by inserting the rear cord plug 200 into the jack of the calling line 90 such as jack J' and actuates her talk and dial key 204 in order to connect her headset to the calling line and learn the nature of the desired connection. Upon learning that a subscriber whose line terminates at another 95 P. B. X. is desired, the attendant tests for an idle tie line leading to the desired P. B. X. and on finding one she inserts plug 220 of the front end of her cord into jack 500 of the idle tie line. The actuation of key 204 100 performs the same functions as described in the previous connections and need not be repeated here.

When plug 220 is inserted into jack 500 a circuit is established for relay 501 over 105 the local jack contacts. In attracting its armatures 520 and 521 relay 501 short circuits condensers 530 and 531 and connects the pulsing relay 504 to the front contacts of relay 508. At its armature 522 it causes 110 relay 505 to operate in an obvious circuit, which in turn causes relay 506 to energize and connect ground to the sleeve of jack 500 through the winding of relay 507. Relay 506 in operating causes relays 510 and 508 115 to operate in a circuit extending from battery, through the winding of relay 510, right hand armature and back contact of relay 509, conductor 511, winding of relay 508, armature and front contact of relay 506 to ground. Relay 510 locks up independent of relay 509, whereas relay 508 connects the tip and ring conductors of the front end of the cord circuit to the pulsing relay 504. The attendant then actuates the 125 dial 348 in accordance with the digit or digits to be dialed, whereupon the connection is established in the well known manner.

The attendant receives supervision on lamp 206 from her local P. B. X. subscriber 130

in the same manner as described in the preceding connections and upon receipt of a disconnect signal at the termination of the connection she withdraws plug 220 from jack 500 causing all the relays, operated, to release. In this connection it will be noted that relays 202, 207 and 507 do not operate. The calling subscriber therefore receives talking battery from battery associated with 10 armature 223 of relay 202.

Connection from C. O. through one P. B. X. to another (attendant dialing over rear end).

15 If the call just described had originated at a central office and the attendant had been signaled by the illumination of a lamp such as 404 she would necessarily have answered the call by inserting the front cord plug 220 into the jack 400, in such a case it is necessary that the attendant's cord circuit be capable of completing the connection over the tie line by permitting her to dial over the rear cord.

20 25 Assuming that the P. B. X. attendant has received a request from a central office operator to complete a connection to another P. B. X., she tests for an idle tie line in the well known manner, and finding one she inserts plug 200 of her cord into jack 500 of the tie line and actuates the through dialing key 210. It is assumed that the attendant has held the talk and dial key 204 actuated. The insertion 30 of plug 200 into jack 500 causes relay 501 to operate in a circuit extending from battery, winding of relay 501, conductor 502, local contact and spring of jack 500 to ground. Relay 501 in attracting its armatures 520 and 521 short circuits the condensers 530 and 531 and connects the pulsing relay 504 to the front contacts of relay 508. In attracting its armature 522, relay 501 establishes an obvious circuit for relay 505, which in operating establishes an obvious energizing circuit for relay 506. At its armature 523, relay 501 causes relay 509 to operate in a circuit extending from battery, lamp 206, back contact and armature of relay 201, sleeve contacts of plug 200 and jack 500, armature 523 and front contact of relay 501, right hand winding of relay 509, armature 522 and front contact of relay 501 to ground. Relay 506 in operating connects ground to the sleeve contact of jack 500, by way of the winding of relay 507, which relay operates in the sleeve circuit just traced, to ground over the armature and front contact of relay 506. Relay 507, in operating, connects the ground on the lower armature and back contact of relay 508, to the winding of relay 510 which thereupon operates and connects the same ground which effected its operation, to the upper terminal of relay 508 so that relay 508 does not operate, since

its lower terminal is also connected to ground at the armature and front contact of relay 506. Lamp 206 is illuminated in the circuit previously traced for relay 507.

When keys 204 and 210 are actuated a 70 circuit is established for relay 363 extending from battery, winding of relay 363, conductor 280, lowermost alternate contacts of key 204, conductor 281, contacts 282 of key 210, conductor 283, back contact and armature of relay 201, sleeve contacts of plug 200 and jack 500, winding of relay 507, to ground over the armature and front contact of relay 506. Relays 212 and 213 also operate as a consequence of the actuation of key 204 (as described hereinbefore), so that with the added operation of relay 363, due to the actuation of both keys 204 and 210, the left hand windings of repeating coil 365 and resistance element 364 are bridged 80 across the front end of the cord by way of the uppermost and lowermost armatures and front contacts of relay 363, conductors 253 and 254, and the make-before-break contacts 217 and 218 of relay 212. This 90 bridge acts as a holding bridge for the central office switches. In attracting its inner upper armature, relay 363 establishes an obvious circuit for relay 352. Relay 352 operates and at its outermost armatures and back contacts removes the bridge including 95 the retardation coil 351 from across the tip and ring conductor of the front end of the cord. The coil 351, however, is now bridged 100 across the rear end of the cord.

It will be noted that when relay 352 operated, the circuit for relay 363 was transferred from the ground on the armature and front contact of relay 506 by way of the winding of relay 507, to the ground on the 105 uppermost alternate contact of key 210. This new circuit may be traced from grounded battery, winding of relay 363, inner upper armature and front contact of relay 352, conductor 295, contact 260 of key 204, ground over the contacts 261 of key 210. The effect of this transfer is to shunt out relay 507, which on releasing permits relay 508 to energize in a circuit extending from grounded battery, winding of relay 510, front contact and armature of relay 510, winding of relay 508 to ground over the armature and front contact of relay 506. The operation of relay 508 will therefore take place immediately following the operation of relays 352 and 363 so that relay 504 is not cut through to receive the dial impulses until relays 352 and 363 have operated to cut off the central office battery. The reason for delaying the connection of the pulsing relay 504 to the rear end (or dialing end in this case) of the cord K is to prevent this relay from responding to the central office battery and thereby effecting 120 a false connection.

In order to dial over the rear end of the cord on a connection from a central office to another P. B. X. it is therefore necessary first, to supply the central office switches with a holding bridge; this is accomplished by the actuation of relay 363 which connects the left hand windings of repeating coil 365 and resistance element 364 across the front end of the cord circuit. Second, the pulsing relay of the tie line must not be connected to the rear end of the cord until central office battery is disconnected from the front end of the cord; this is accomplished by the peculiar relay arrangement associated with applicant's tie line and by the operations of relays 352 and 363.

The attendant now operates the dial 348 in accordance with the desired number and as it is moved from normal position relays 339 and 350 are energized as in the previous case. Relay 335, however, does not operate as its energizing circuit is opened at the lowermost armature and back contact of relay 352. The operation of relay 350 places the dialing contacts directly across the conductors 233 and 234 by way of the normal make-before-break contacts of relay 335, the conductors 233 and 234 being connected to the tip and ring conductors of the rear end of the cord by way of the front contacts and outer upper and lower armatures of relay 212. The interruptions of the dial contacts as the dial restores to normal cause the intermittent operation of pulsing relay 504, thereby setting the automatic switches in the well-known manner to effect the desired connection. It is believed unnecessary to trace the connection any further or to describe the disconnect operations since these are quite obvious in view of the preceding descriptions.

What is claimed is:

1. In a telephone system, a plurality of cord circuits, a dialing circuit common to said cord circuits, an operator's telephone set, a key for each of said cord circuits, a relay controlled by one of said keys for connecting said set and said dialing circuit to a corresponding cord circuit, and means controlled by the operation of said relay for rendering a corresponding relay in another of said cord circuits inoperative to connect said set and said dialing circuit with another of said cord circuits.
2. In a telephone system, a plurality of cord circuits, a key for each of said cord circuits, dialing equipment common to said cord circuits, a relay in each of said cord circuits normally responsive to the actuation of a corresponding cord key, a relay in said dialing equipment, and means responsive to the actuation of one of said keys for operating the relay associated with the dialing equipment, thereby rendering the actuation of a key in another cord circuit ineffec-

tive to operate its corresponding cord relay.

3. In a telephone system, a plurality of cord circuits, dialing equipment common to said cord circuits, a key for each of said cord circuits, a bridge circuit associated with said dialing equipment, a relay for each of said cord circuits responsive to the actuation of one of said cord keys for connecting said bridge with a corresponding cord circuit, and means controlled by said relay for rendering the operation of a second cord key ineffective to connect said bridge with a second cord circuit. 70 75

4. In a telephone system, a cord circuit having a front and a rear end, dialing equipment, a dial key associated with said cord circuit and adapted upon actuation to connect said dialing equipment to the front end of said cord, a second key, and means responsive to the joint operation of said keys 80 85 for associating said dialing equipment with the rear end of said cord.

5. In a telephone system, a cord circuit having front and rear ends, dialing equipment, a repeating coil, a key in said cord circuit normally operative to connect said dialing equipment to the front end of said cord, a second key, and means responsive to the operation of said first and second keys for connecting said dialing equipment to the rear end of said cord and a bridge including 90 95 said repeating coil to the front end of said cord.

6. In a telephone system, a telephone exchange, a machine switching exchange, means at said telephone exchange including a trunk circuit and a plurality of automatic switches for establishing a connection through said machine switching exchange, a signaling device, and means associated with said trunk circuit for rendering said signaling device inoperative upon the release of said automatic switches when said connection is terminated. 100 105

7. In a telephone system, a telephone exchange, a machine switching exchange, means at said telephone exchange including a trunk circuit and a plurality of automatic switches for establishing a connection through said machine switching exchange, a signaling device, and a bridge circuit associated with said trunk circuit for rendering the surges caused by the release of said automatic switches at the termination of said connection, ineffective in actuating said signaling device. 110 115

8. In a telephone system, a trunk circuit having an alternating current bridge circuit normally connected thereto, said trunk adapted to function with automatic switches 125 in the establishment of a telephone connection, a double wound relay in said bridge circuit, one of said windings adapted to maintain said relay operated after its other winding has been energized by alternating 130

- current incoming over said trunk, and both of said windings being so related as to prevent said relay from being permanently operated when said other winding is energized by electrical surges caused by the release of the aforementioned switches at the termination of a connection. 5
9. In a telephone system, a telephone exchange, a machine switching exchange, means at said telephone exchange including a trunk circuit and a plurality of automatic switches establishing a connection through said machine switching exchange, an alternating current relay normally connected 10 across said trunk circuit and disconnected therefrom when said trunk is seized in establishing a connection through said machine switching exchange, means responsive to the release of said automatic switches at 15 the termination of said connection for reversing current over said trunk, said alternating current relay being subjected to said current reversal, and means including a secondary winding on said relay for rendering 20 said relay unresponsive to the current produced by said reversal. 25
10. In a telephone system, a central office exchange, automatic switches therein, a second exchange, a tie line terminating therein 30 and leading to a third exchange, a pulsing relay associated with said tie line, means at said second exchange for extending a connection from said first exchange to said third exchange, said connection including said automatic switches and said tie line, and means 35 at said second exchange for delaying the connection of said pulsing relay to said tie line until the central office battery associated with the established connection is disconnected 40 therefrom. 45
11. In a telephone system, a central office exchange, automatic switches therein, a second exchange, a tie line terminating therein and leading to a third exchange, a pulsing 50 relay associated with said tie line, means at said second exchange for extending a connection from said first exchange to said third exchange, said connection including said automatic switches and said tie line, a dial, 55 and means at said second exchange for supplying a holding bridge for said central office switches and for thereafter connecting the pulsing relay of said tie line to said dial. 60
12. In a telephone system, a telephone exchange, a tie line terminating therein, a pulsing relay associated with said tie line, an operator's cord circuit having front and rear ends, a dial, a key in said cord circuit for connecting a bridge across said cord circuit, a 65 second key, means responsive to the joint operation of said keys for connecting a bridge across the front end of said cord, and thereafter connecting said dial to the pulsing relay of said tie line, and means responsive to 70 the actuation of said dial for disconnecting said first mentioned bridge from said cord circuit. 75
13. In a telephone system, a telephone exchange, a normally discontinuous tie line 70 terminating therein, an operator's cord circuit, dialing equipment, a relay in said tie line, means responsive to the connection of said cord circuit with said tie line for connecting a shunt about said relay, and key 75 controlled means for connecting a bridge across one end of said cord circuit and thereafter removing the shunt from said relay, whereby said relay operates to render said tie line continuous. 80
14. In a telephone system, a telephone exchange, a tie line outgoing from said exchange, a cord circuit having a plurality of keys, dialing equipment, means responsive to the actuation of one of said keys for associating said dialing equipment with the front end of said cord when said front end is connected to said tie line, and means responsive to the joint operation of said keys for associating said dialing equipment with the rear 85 end of said cord when said rear end is connected to said tie line. 90
15. In a telephone system, a telephone exchange, a second exchange, a tie line interconnecting said exchanges, a cord circuit 95 having front and rear ends, a key in said cord circuit, dialing equipment, and means responsive to the actuation of said key for associating said dialing equipment with the front end of said cord whereby a connection 100 may be extended from said first exchange through said second exchange by way of said tie line. 100

In witness whereof, I hereunto subscribe my name this 23rd day of October A. D., 1923.

WALTER P. ALBERT.
